A. B. FISHWICK

RADIO APPLIANCE

Filed Nov. 12, 1923

INVENTOR:

Arthur B. Fishwick

BY

George Belin

ATTORNEYS.

UNITED STATES PATENT OFFICE.

ALBERT B. FISHWICK, OF CINCINNATI, OHIO.

RADIO APPLIANCE.

Application filed November 12, 1923. Serial No. 674,225.

My invention relates to devices or structures for use in connection with radio equipment, particularly as wave interceptors, in place of antennæ either aerial or loop.

5 It is my object to provide an inexpensive and yet highly efficient device in which a series of wires are held on a linear member, and which device can be directly, inductively or electro-statically coupled in radio work 10 for the purpose of intercepting of either Hertzian waves, or any induced waves within in the radio set.

In its essence my invention consists in the device itself aside from the methods of use 15 thereof, but I have found in my experiments several very interesting modes of use, which demonstrate the value of my construction. It is not my purpose, however, to deal with theories in this specification, but merely to 20 describe the mechanism itself, and several modes of use thereof. Among other things the device retains a series of equally inter-spaced wires between webs of fabric, and bound in with a protective and insulating 25 layer of bituminous nature, preferably asphalt.

I accomplish my objects by that certain construction and arrangement of parts to be hereinafter more specifically pointed out and 30 claimed.

In the drawing:

Figure 1 is a plan view of the device extended.

Figure 2 is a section on the line 2—2 of 35 Figure 1.

Figure 3 is a detail section of the condenser or inductive method of coupling up my device.

Figure 4 is a diagram, partly a perspective, 40 indicating the method approved by me, of using the device in place of an aerial antenna, wherein a direct coupling is employed.

Figure 5 is a diagram, illustrating the approved use of my device as an interceptor, 45 between the primary of a radio set and the ground, omitting the usual antenna connection. In this form the inductive or condenser mode of coupling is used.

In forming my device, I employ a special 50 machine, which is known in the art, and while pasting together two webs of paper by means of asphalt, I deposit between the webs in the plastic asphalt, a series of wires of the desired number, and of the desired spacing.

55 Thus I have the paper webs 1, 1, the as-

phalt layer 2, and the interspaced wires 3. The number of strands and the spacing will be arranged according to the desired wave length limits of a radio set. The outer webs may be of paper, or more expensive fabric, 60 is desired, paper being perfectly satisfactory. The interposed binding layer or asphalt retains the wires in position, and in addition insulates them highly against each other, in the plane of the paper, and furthermore, insulates them all the way around. 65

In one form of the device, a brass binder, or other form of conductive material binder is used, same being a fold of metal 4. In mounting this brass strip over the paper, in 70 this form I insert a fold of insulating material 5, in the holder, and then bend it over the end of the paper. The brass strip will then extend across the end of the paper without direct connection to the wires. The binding post 6 of any usual form will be inserted 75 through the brass strip, but not in position to contact with any of the wires.

This form I have termed a condenser type, or electrostatic coupling, and I have found 80 that an excellent method of "hooking up" the device is to roll it around a core, or roll it and insert it into a paper tube indicated at 7, with the wire from the ground end of the primary 8 connected to the terminal or binding post 6, and another wire run from the antenna end of the primary to the ground, as indicated at 9. 85

An audio set so coupled, so far as my experiments have gone, will be very powerfully 90 energized by radio waves, although by what theory I do not know. In my experiments I have used a piece of the paper 12 inches wide, with fifteen wires, three quarters of an 95 inch apart, and the paper a little over six feet long, coiled inside of a standard mailing tube of about two and one half inch internal diameter. The wires are carbon steel piano wires of very fine gauge.

In this method of use the device of my invention is the only wave intercepting device 100 employed.

I find that my device can be hung up so as to fall straight, and be used as an antenna, being coupled to the primary of the set in the 105 usual way that an antenna is coupled up. This I have shown in Figure 4, wherein the one web of paper is brushed away as indicated at 10, leaving the wires 3 exposed. The brass strip or fold is then secured to the paper 110

without insulation, the paper being bent back double at the end to expose the wires fully to the brass. The terminal post will be the same as before, but in this instance, the coupling of the wires of the paper with the primary of the set will be a direct coupling.

While I have used a primary coil, as indicating the first instrument of a radio set, this is merely for purposes of illustration. My device will have use in induction work generally, as the secondary of a transformer, but the value to radio work, as so far developed has been its function in intercepting Hertzian waves. I find an improvement in static noises, when using my device, although whether this is a function of the device, or of the chance arrangement of my experimental models, I do not know.

Having thus described my invention, what I claim as new and desire to secure by Letters Patent, is:—

1. An article of manufacture for use as a radio antenna or wave reception unit, comprising a series of strands of wire arranged in interspaced parallel relation, flexible webs united by a binding layer about said wires, to form a flat strip and to permanently space said wires, and a conductive element laid across the said strip, but conductively out of connection with the several wires, said conductive element serving as a capacity element to be secured to a radio receiving set.

2. An article of manufacture for use as a radio antenna or wave reception unit, comprising a plurality of webs of paper, secured together by a binding layer of bitumin, and a series of wires arranged in interspaced parallel relation within the said binding layer, and means common to all of said wires

for electrically connecting said wires to a radio receiving set.

3. An article of manufacture for use as a radio antenna or wave reception unit, comprising a plurality of webs of paper, secured together by a binding layer of asphalt-like material, and a series of wires arranged in interspaced parallel relation within the said binding layer, and means common to all of said wires for electrically connecting said wires to a radio receiving set, said means comprising a strip of conductive material secured to the webs across the wires, but out of contact with the wires.

4. A material from which electric wave sensitive units may be formed comprising webs of paper secured together by a binding layer of dielectric adhesive of bituminous nature and strands of interspaced wires extending through said material, within the binding layer.

5. An article of manufacture comprising a coiled strip of material formed of a plurality of webs bound together by a binding layer, and a series of parallel interspaced wires extending through the binding layer, lengthwise of the material, and a strip of conductive material secured across the wires, but out of electrical contact connection therewith.

6. An article of manufacture comprising an antenna in the form of a flat flexible strip, formed of layers of flexible material, united by a binding layer of asphalt-like substance, strands of interspaced, parallel wires extending through said binding layer, lengthwise of the strip, and a metal binding mounted over the end of the strip, same being insulated from contact with the wires.

ALBERT B. FISHWICK.
